J. E. KENNEDY

TRAFFIC SIGNAL

Filed Aug. 7, 1922

JOHN F. KENNEDY.

Inventos

By Edward Reed

Attorney

UNITED STATES PATENT OFFICE.

JOHN ELDY KENNEDY, OF DAYTON, OHIO.

TRAFFIC SIGNAL.

Application filed August 7, 1922. Serial No. 580,351.

To all whom it may concern:

Be it known that I, JOHN E. KENNEDY, a citizen of the United States, residing at Dayton, in the county of Montgomery and State of Ohio, have invented certain new and useful Improvements in Traffic Signals, of which the following is a specification, reference being had therein to the accompanying drawing.

10 This invention relates to traffic signals for automobiles and the like.

One object of the invention is to provide a signal which will be concealed from view when not in use.

15 A further object of the invention is to provide such a signal which will be compact in form and easily operated.

A further object of the invention is to mount the signal as a whole in a housing 20 which is normally closed by a door and to provide means controlled by the signal for opening and closing the door of the housing.

Other objects of the invention will appear as the mechanism is described in detail.

25 In the accompanying drawings Fig. 1 is a side elevation of the mechanism showing the same in its extended position, with the housing in section; and Fig. 2 is a plan view of the mechanism, partly broken away, 30 showing the same in its extended position and showing the housing in section.

In these drawings I have illustrated one embodiment of my invention and the construction here shown is substantially the 35 same as that shown in my copending application for patent filed Aug. 20, 1921, Serial No. 493,827, of which application the present application is a continuation in so far as the mechanism is common to both applications.

40 It will be understood that the particular mechanism here shown has been chosen for the purpose of illustration and that the invention may take various forms without departing from the spirit thereof.

45 In that embodiment of the invention here illustrated I have shown the signal and its associated mechanism as mounted in a pocket formed in the side wall of an automobile. Preferably, but not necessarily, this pocket

50 comprises a casing, or housing, which is mounted in the body of the automobile, which has an opening formed therein to receive the same. If the shape of the body permits it, the outer end of the housing may be

55 substantially flush with the wall of the body,

or the end of the housing may project more or less beyond the wall of the body. The opening through which the signal is projected is closed by a door which, when the mechanism is mounted in a casing or housing, is preferably attached to the outer end 60 of the housing, but which may be attached directly to the wall of the vehicle body.

In the present construction the signal and its projecting mechanism are mounted on 65 a housing 1 which is arranged wholly within the body of the vehicle, the latter being provided with an opening 2 to receive the same and the outer end of the housing being sub-

stantially flush with the wall of the body A. 70 The housing is preferably mounted in the body in such a position that it will project into the same in the rear of the seat so that it will not offer an obstruction in the interior of the vehicle.

The signal itself may be of 75 any suitable character and may be mounted on an extensible support of any suitable kind. As here shown the signal is in the form of a casing 3 having a bull's eye 4 in the front and rear walls thereof and adapted 80 to contain an electric lamp, which is not here shown, as it forms no part of the invention.

This signal is mounted upon lazy tongs 5, the rear arms of which are mounted upon the rear wall of the housing. One arm of 85 the lazy tongs is slidably connected with the wall 6, as shown at 7, to permit of the folding of the lazy tongs and the retraction of the signal. The lazy tongs, or extensible sup-

port, may be actuated in any suitable manner to project and retract the signal. As 90 here shown a bell crank lever 8 is mounted on a bracket 9 in the lower portion of the housing and has one arm connected by a link 10 with the lazy tongs and has its other arm connected with an operating rod 11 which

connects with an operating mechanism which may be of any suitable kind, such, for example, as that shown in the above mentioned 95 application. Connected with the link 10 is a spring 12 which is also connected with the wall of the housing so as to draw the link 10 forwardly and thus tend to expand the lazy tongs. This spring may be of sufficient

100 strength to project the signal, but when it is used in connection with an operating mechanism comprising a spring, such as shown in the above mentioned application, it will probably be of a lighter construction and will merely assist in the projection of the signal. 110

It will be apparent that the downward movement of the operating rod 11 will force the link 10 rearwardly and thus contract the lazy tongs and retract the signal.

5. The housing 1 is preferably provided with a suitable door, which will give the device a finished appearance when the signal is in its retracted position. As here shown, the door 13 is hinged to one of the vertical edges 10 of the forward end of the housing and is acted upon by a spring 14 which tends normally to close the same, and to retain the same in its closed position. The opening and closing of the door is controlled by the 15 movement of the extensible support for the signal and the controlling means is preferably of such a character that the door will be locked in its open position and held against closing movement until the signal 20 has been retracted far enough to clear the outer edge of the door, thus preventing the door from being moved into the path of the signal after it is retracted. As here shown, the door operating mechanism comprises a 25 toggle which consists of one arm, 15, of a bell crank lever pivoted on a bracket 16 in the lower part of the housing, and a link 17 pivotally connected at one end with the arm 15 and pivotally connected at the other end 30 on a horizontal axis with a lug, or hinged plate, 18 which is pivotally connected on a vertical axis with the door, as shown at 19. The arrangement of the parts is such that when the door is in its open position the 35 several centers of the toggle will be so arranged as to lock the door against closing movement. To straighten the toggle and open the door the second arm, 20, of the bell crank lever extends upwardly into the path 40 of a lug 21 carried by the extensible support and so arranged that the expanding movement of the support will actuate the bell cranked lever to straighten the toggle, thus forcing the door into its open position. A 45 pin 22 carried by the extensible support is so arranged that it will engage the arm 20 of the bell crank lever and move the same rearwardly to break the toggle and permit the door to be closed when the signal is re- 50 tracted. This pin is so arranged on the extensible support that it will not engage the arm 20 of the bell crank lever until the signal has been retracted far enough to carry it past the outer edge of the door 13. The 55 toggle being in a straight position will hold the door open after the lug 21 has been moved away from the arm 20 and until the toggle is broken by the contact of the pin 22 with the arm 20.
60. The construction is very simple and easily operated. When not in use the signal mechanism is entirely concealed so that it does not present an unsightly appearance, the door operating mechanism being so controlled that the door will be closed at all

times when the signal is retracted. I have shown and described but one signal, but it will be understood that in practice a signal will usually be mounted on each side of the vehicle. The signals may, if desired, be controlled by a common operating mechanism, as shown in the above mentioned application.

70 While I have shown and described one embodiment of my invention I wish it to be understood that I do not desire to be limited to the details thereof as various modifications may occur to a person skilled in the art.

75 Having now fully described my invention 80 what I claim as new and desire to secure by Letters Patent is:

85 1. In a device of the character described, a housing, a door for said housing, an extensible support mounted within said housing, a signal carried by said support and adapted to be projected beyond said housing by said support, and a toggle 90 connected with said door and controlled by the movement of said extensible support.

95 2. In a device of the character described, a housing, an extensible support mounted within said housing, a signal carried by said support, means for actuating said support to project and retract said signal, a door for said housing, a toggle connected with said door and arranged to lock said door in its open position, an actuating member connected with said toggle, and means carried by said extensible support to 100 impart movement to said actuating member.

105 3. In a device of the character described, a housing, an extensible support mounted within said housing, a signal carried by said support, means for actuating said support to project and retract said signal, a door for said housing, a toggle connected with said door and arranged to lock said door in its open position, an actuating member connected with said toggle, a 110 projection carried by said extensible support to move said actuating member in one direction when said support is extended, and a second projection carried by said extensible support to engage said actuating member when said support is being retracted, said second projection being so arranged with 115 relation to said actuating member that it will not engage the same until said extensible support has been partially retracted.

120 4. In a device of the character described, a housing having a door at the outer end thereof, lazy tongs connected at one end with the inner wall of said housing, a signal carried by the other end of said lazy tongs, means for extending and retracting said lazy tongs, a toggle having one arm connected with said door for movement about both a horizontal and a vertical axis, an actuating arm connected with the first men- 125 130

tioned arm of said toggle, and projections carried by said lazy tongs and arranged respectively to engage said actuating arm when said lazy tongs is expanded and retracted.

5. In a device of the character described, a housing, an extensible support mounted in said housing, a signal carried by said support, a door for said housing, 10 a spring to close said door, a toggle to open said door and lock the same in its open position, and means controlled by said extensible support to actuate said toggle.

6. The combination with a vehicle body 15 having an opening in the wall thereof, of a signal, an extensible support for said signal and, therewith, lying normally within said body, and means to actuate said support to project said signal through the opening in the wall of said body.

7. The combination of a vehicle body having an opening in the wall thereof, of a housing mounted within said body in line with said opening, a signal, an extensible 25 support mounted within said housing and adapted to support said signal normally within said housing, and means to actuate said support to project and retract said signal.

8. The combination of a vehicle body having an opening in the wall thereof, of a housing mounted within said body in line with said opening, a signal, an extensible support mounted within said housing and 30 adapted to support said signal normally within said housing, means to actuate said support to project and retract said signal, a door for said opening, and means con-

trolled by the movement of said signal to open and close said door. 40

9. The combination with a vehicle having a pocket in one side thereof, of an extensible support mounted within said pocket, a signal carried by said support, and means for actuating said support. 45

10. The combination with a vehicle having a pocket in one side thereof, of an extensible support mounted within said pocket, a signal carried by said support, means for actuating said support, and a door to close 50 the outer end of said pocket when said signal is in its retracted position.

11. The combination with a vehicle having a pocket in one side thereof, of an extensible support mounted within said 55 pocket, a signal carried by said support, means for actuating said support, a door to close the outer end of said pocket when said signal is in its retracted position, and means controlled by said extensible support to open 60 and close said door.

12. In a device of the character described, a housing, lazy tongs mounted at one end in said housing, a signal carried by the other end of said lazy tongs and adapted to be 65 carried thereby into and out of said housing, a spring acting on said lazy tongs to extend the same, a bell crank lever mounted within said housing and having one arm connected with said lazy tongs, and an operating rod connected with the other arm of said bell crank lever. 70

In testimony whereof, I affix my signature hereto.

JOHN ELDY KENNEDY.
